UNITED STATES PATENT OFFICE.

CHRISTIAN ECKSTEIN, OF WEIDEN, GERMANY, ASSIGNOR TO THE FIRM OF AKTIEN-
GESELLSCHAFT PORZELLANFABRIK WEIDEN, GEBRÜDER BAUSCHER, OF WEIDEN,
GERMANY.

POTTERY-MOLDING MACHINE.

1,129,797.

Specification of Letters Patent. Patented Feb. 23, 1915.

Application filed July 31, 1914. Serial No. 854,231.

To all whom it may concern:

Be it known that I, CHRISTIAN ECKSTEIN, subject of Germany, residing at Weiden, Bavaria, Germany, have invented certain 5 new and useful Improvements in Pottery-Molding Machines; and I do hereby declare the following to be a full, clear, and exact description of the invention, such as will enable others skilled in the art to which it 10 appertains to make and use the same.

My invention relates to an improved machine for manufacturing vessels from plastic substances, such as clay and the like.

The object of my invention is to provide 15 an apparatus wherein I dispense entirely with the use of a mold and core, the shaping being performed solely with the aid of rolls, which act upon the plastic mass internally and externally. To this end I use, in combination with the usual revolving disk or 20 potter's wheel, two or more vertical or inclined rolls for acting on the outside of the work, and a roll or rolls for acting on the inside, the rolls being disconnected from the 25 disk, so that the latter revolves the work between the internal and external rolls, which may, during the operation, be moved longitudinally. In the course of the operation the rolls are adjusted in relation to each 30 other, preferably with the aid of a templet or pattern plate, for the purpose of fashioning the work. The rolls and the pattern plate or templet are exchangeable, and the 35 longitudinal section of the rolls corresponds with the final shape of the object formed. I may provide a horizontal or approximately horizontal roll or rolls above the revolving disk, to act on the work at the top.

An embodiment of the invention is shown 40 in the accompanying drawings, in which—

Figure 1 is a plan view, and Fig. 2 a side view, partly in section. Figs. 3 and 4 show details.

In the drawings *a* designates the revolving disk, upon which a lump of the suitably prepared plastic mass is placed. A frame *b*, which is vertically movable on a pillar *o* and can be raised by means of a crank *m*, pinion *v*, and rack *p*, is thereupon lowered by means 45 of two pivoted arms *c*, *d*, so that four rolls *e*¹, *e*², *e*³, *e*⁴ carried by the frame nearly meet the disk *a*. The said rolls are arranged in pairs, *e*¹, *e*² and *e*³, *e*⁴, each depending from a movable holder, and the arms *c* and *d* are 50 connected to these holders, so that the two 55

pairs of rolls can be drawn apart, to lie at the sides of the lump of plastic material, whereas another roll, designated *f*, carried by the frame *b*, is plunged into the lump. The frame also carries a horizontal roll *g*. 60 By moving the two pairs of rolls *e*¹, *e*² and *e*³, *e*⁴ toward the roll *f* the work is centered and squeezed so as to become lengthened in the upward direction. The roll *f* may be vertically movable in the frame, or may be 65 adjustably fixed to the same, and by lowering it on to the work the mass is squeezed from above. The lateral and vertical squeezing operations are preferably performed alternately several times, whereby the mass is 70 suitably prepared for uniform molding.

A templet or pattern plate *h* is hinged to the table *w* on which the disk *a* revolves, the templet being fixed by a lug *z* to a spindle *i*, which can be fixed by means of a pin *k* to 75 hold the templet in a vertical position, as shown in Figs. 2 and 4. The arms *c* and *d* are laid against the lateral edges of the templet, and connected to each other by a coiled spring *s*, which holds them against the said 80 edges, so that the templet determines the diameter of the article molded by the rolls.

A crank *l*, bevel gears *n*, and worm *u* enable the roll *f* to be adjusted in a horizontal direction in relation to the rolls *e*¹, *e*², *e*³, 85 *e*⁴, for determining the thickness of the wall of article molded.

By turning the crank *m* the frame *b*, with the rolls, can be raised during the molding operation, so that the mass is driven up between the rolls *e*¹, *e*², *e*³, *e*⁴ and the roll *f*, and the desired shape is obtained. Some objects may be molded without moving the frame upward. The weight of the frame is balanced by weight (not shown) attached 90 to a cord *r*. All the rolls are adjustable and exchangeable, and any desired number of rolls may be used.

What I claim as my invention and desire to secure by Letters Patent of the United States is:—

In a pottery molding machine, the combination of a horizontal revoluble disk adapted to support plastic material, a frame vertically movable in relation to said disk, oppositely disposed rolls for acting against the outer surface of said plastic material, means whereby said rolls are slidably suspended from said frame and are movable toward and from each other, a roll suspended from 105 110

said frame and adapted to act against the inner surface of said plastic material, means for moving said last named roll toward and from either of said first mentioned rolls, and
5 an additional, suspended, horizontal roll adapted to act against the upper edge of said plastic material.

In testimony whereof I hereunto affix my signature in the presence of two witnesses.

CHRISTIAN ECKSTEIN.
